UNITED STATES PATENT OFFICE

169,003

FOOD BASKET

Hugh J. Keegan, South Boston, Mass., assignor
to National Tag & Label Corporation, Water-
town, Mass., a corporation of Massachusetts

Application March 29, 1952, Serial No. 19,109

Term of patent 3½ years

(Cl. D58—4)

To all whom it may concern:

Be it known that I, Hugh J. Keegan, a citizen of the United States, and a resident of South Boston, county of Suffolk, and Commonwealth of Massachusetts, have invented a new, original, and ornamental Design for a Food Basket, of which the following is a specification, reference being had to the accompanying drawing, forming a part hereof.

In the drawing:

Fig. 1 is a plan view of a food basket showing my new design;

Fig. 2 is a side view of the same with the near side partly broken away; and

Fig. 3 is an end view of the same with the near end portion omitted.

My design is characterized by the configuration of the combination dividing unit and cup holder.

I claim:

The ornamental design for a food basket, substantially as shown and described.

HUGH J. KEEGAN.
